UNITED STATES PATENT OFFICE

CARL A. W. BRANDT, OF GREAT NECK, NEW YORK, ASSIGNOR TO THE SUPERHEATER COMPANY, OF NEW YORK, N. Y.

HIGH-PRESSURE LOCOMOTIVE

Application filed January 24, 1925. Serial No. 4,584.

My invention relates to locomotive boilers, particularly to the type adapted to operate at high pressures, although it is to be understood that the present invention is equally applicable in boilers to be operated at any desired pressure.

In meeting the demands for greater locomotive boiler capacity, the limit of size imposed by bridge and tunnel clearances has already been reached. The limit has also been arrived at for safe working pressures in existing types of boilers, and further capacity per unit has been sought by the addition of boiler auxiliaries, such as superheaters, feed water heaters and the like, which, until recent years, were applied only in stationary power plant practice. Modern railroad practice, however, calls for locomotives of greater capacity than are at present available, and the rapidly increasing cost of fuel has created a necessity for greater boiler efficiency as well, which present locomotives cannot meet.

The object of my present invention is, therefore, the provision of a boiler in which increased capacity and efficiency is obtained by the arrangement and distribution of the heating surfaces of the boiler in such manner as to secure the most advantageous circulation of water throughout the boiler, and the most effective heat transfer from the combustion gases to the contents of the boiler in accordance with the well known counterflow principle of heat transfer. A further object of my invention is the provision of a boiler which, by the elimination of all stayer surfaces, is capable of being operated at pressures of from 600 to 800 lbs. per square inch or even higher and which thereby provides the advantages to be derived from the use of high pressure steam. Other and further objects will appear more fully in connection with the following detailed description of specific embodiments of my invention, which are illustrated in the accompanying drawings, of which:

Fig. 1 is a longitudinal vertical central section of a preferred form of my invention taken on the line 1—1 of Fig. 2, a portion 50 of the figure being shown in elevation.

Fig. 2 is a vertical transverse section taken on the line 2—2 of Fig. 1;

Fig. 3 is a vertical transverse section taken on the line 3—3 of Fig. 1;

Fig. 4 is a view similar to Fig. 1 of a modified form of my invention;

Fig. 5 is a composite vertical transverse section, the left half of which is taken on the line 5^a—5^a of Figs. 1 and 4 and the right half of which is taken on the line 5^b—5^b of Figs. 1 and 4;

Fig. 6 is a composite vertical transverse section, the left half of which is taken on the line 6^a—6^a of Figs. 1 and 4, and the right half of which is taken on the line 6^b—6^b of Figs. 1 and 4;

Fig. 7 is a composite vertical transverse section, the left half of which is taken on the line 7^a—7^a of Fig. 4 and the right half of which is taken on the line 7^b—7^b of Fig. 4; and

Fig. 8 is a view in elevation of a portion of the structure shown in Fig. 1.

As may be seen by an inspection of Fig. 1, I have divided the heating surface of the boiler into four units, consisting of a water tube unit forming a furnace and combustion chamber, a fire tube evaporating unit located forwardly of said water tube unit and spaced therefrom, a superheater unit located in the space provided between the two units just mentioned, and an economizer unit located forwardly of said fire tube evaporating unit.

The section forming the fire box and combustion chamber of the boiler resembles in general form the cross drum type of stationary boiler with the central tubes removed therefrom, and eliminates the flat stayed surfaces usual in the ordinary form of locomotive fire box section, substituting therefor a tube and header construction, adapted to be safely operated at high pressures and providing a rapid and well defined water circulation within the unit.

The side walls of this unit are formed by horizontally inclined tubes, 1 of comparatively large diameter, contacting to form a solid water cooled wall. At their ends these tubes are swaged down to a smaller

diameter, as at 2, in order that they may be rolled or otherwise suitably secured in vertical front headers 3, (Figure 5), which form the outer extremities of the front wall of the unit and corresponding rear headers 4 (Figure 3) forming the outer extremities of the rear wall of the unit. This construction further permits sufficient spacing of the tube holes in the headers 3 and 4 to give adequate ligament strength for the pressures contemplated. The roof is formed by a plurality of spaced inclined roof tubes 5 supporting a refractory baffle of any desired form which serves to close the space between the tubes, the tubes being similar in form to the tubes comprising the side walls except for the fact they are bent, as at 7, to provide a short horizontal section in front of the rear header for a purpose to be referred to later.

The roof tubes 5 are secured at their forwards ends to a horizontal transverse header 8 and at their rearward ends to vertical headers 9 which form the central portion of the rear wall of the unit. The rear vertical headers 4 and 9 are nipped at their upper ends into a transverse header 10, and at their lower ends the outer headers 9 are nipped into a second transverse header 11 which is in turn nipped to the inner side of the headers 4. The central headers 9^a are shorter than the headers 9 and at their lower ends are nipped to a short transverse header 12, which is nipped to the inner side of the two inner headers 9, the space between headers 11 and 12 and between the headers 9 providing a fire opening 13.

The forward wall of the unit is formed by a series of short vertical headers 14, which are connected to each other and to the vertical headers 3 by a series of top and bottom transverse nipples, and the transverse header 8, which is supported by the headers 3 to which it is connected by end nipples. The space 15 between the upper ends of headers 14 and the transverse header 8 forms an outlet for the combustion gases.

Horizontally inclined arch tubes 16 connected at their forward ends into the headers 14 and at their rearward ends into headers 9 and 12 support the refractory baffle 17 which serves to direct the gas flow through the unit.

A transverse steam and water drum 18 is mounted above and parallel to the header 8 and is connected thereto and to the headers 3 by a plurality of nipples 19. The rear transverse header 10 extends, as shown in Figure 1, above the level of the roof baffle 6 and is connected to the drum 18 by horizontal circulating tubes 20, which are rolled or otherwise suitably secured in the drum 18 at approximately its horizontal diameter, at which point the water level is normally carried.

In order to carry the side wall tubes 1 to the maximum height and to reduce to a minimum the brick work necessary in the combustion chamber, the roof tubes are bent as previously described to extend forward horizontally some distance from the rear header 9 before sloping downward to the front header 8 and each of the topmost side wall tubes 1^a is placed in the same horizontal plane as the roof tubes, and forms a support for the outer portion of the roof baffle 6. The tubes 1^a cannot be carried rearward beyond the point where the roof tubes are bent, inasmuch as the tubes 1^a lie in the same vertical plane with the outermost circulating tubes 20 and at this point are directly beneath them. In order therefore to accommodate these tubes the outer circulating tubes 20 instead of being integral lengths of tubing, are each composed of two tubular sections 20^a and 20^b secured to intermediate header boxes 21 (see Figure 1) having drop-leg portions which receive the rear ends of the tubes 1^a, the tube section 20^b providing the necessary communication between the tubes 1^a and the header 10.

For the sake of clearness the fuel grate has been omitted from the drawing, and it will further be obvious that any desired form of fuel may be utilized with equal facility, the ignited combustion gases passing upward and rearwardly of the baffle 17, between the extended portion of the arch tubes 16, and then forwardly to the combustion gas outlet 15. It is to be understood, however, that the form of baffling may be altered in any way desired to suit specific individual requirements without departing from the spirit or scope of my invention.

By means of the construction just described I provide a fire box and combustion space which presents substantially entirely water cooled surfaces to the fire on all sides, whereby a maximum amount of heat is absorbed by radiation, and this is accomplished by means which entirely eliminate undesirable flat stayed surfaces and which follow only approved engineering practice. The tubes and drums may be made of seamless tubing, and the headers are preferably of forged or cast steel, the entire structure being capable of withstanding extreme operating pressures.

Inasmuch as the major amount of evaporation takes place in this unit, it is imperative that there be a free, definite and regular water circulation therein, and it will be obvious from Figure 1 that I have provided such a circulation in which the forward headers 3 and nipples 19 function as down-comers receiving water from drum 18 and supplying the evaporating side, roof, and arch tubes, which discharge into the rear uptake headers 4 and 9. The discharge from the up-take headers is received by the cir-

culating tubes 20 through the upper rear transverse header 10 and these tubes together with the drum 18 provide the necessary steam disengaging surface for the separation of the steam and water discharged from the evaporating tubes. It will thus be seen that I have provided a circulation in this section analogous to that of the cross drum stationary boiler, which has proved itself capable of operating satisfactorily at high overload ratings and of responding quickly to extreme fluctuations in load, such as are encountered in locomotive practice.

The fire box unit just described is enclosed in an outer casing, or main shell 22, which is carried forward as shown in Figure 1 and houses the superheater and the fire tube evaporating units as well as the economizer.

The superheater unit is located just forward of the fire box unit and will be described in detail later.

The fire tube evaporating unit, which provides the main water storing capacity of the locomotive, is primarily designed to withstand high operating pressures and in place of the usual single drum of large diameter I have substituted a number of small diameter drums so arranged as to utilize to the maximum extent the clearance space available. As will be noted from Figure 2 the cross section of the locomotive at this point is substantially rectangular, this shape permitting the use of a larger sectional area within given clearance limits than is possible with the use of a cylindrical shell. In the embodiment illustrated I have shown nine fire tube drums 23 with the interstices between these drums and between the outer drums and the main boiler shell 22 occupied by a number of similar drums 24 of smaller diameter, although it is to be understood that the number and relative positions of the drums employed may be varied without departing from the scope of my invention. By the use of these small diameter drums I am able to provide a fire tube evaporating unit capable of withstanding the extremely high operating pressures contemplated, without using drum walls of a thickness greater than normal; that is to say, a thickness of one inch or less. I prefer to use drums, the cylindrical shells of which are formed of seamless drawn metal, and thereby avoid the exposure of riveted seams to the combustion gases.

If desired, the spaces between the exteriors of the several drums may be blocked off by suitable refractory baffles, in which case all of the combustion gases will be forced through the fire tubes; the spaces may be left open, in which case a portion of the combustion gases will pass between the drums and make useful as evaporating surface the exterior surfaces thereof, or a portion only

of the interdrum spaces may be blocked off, where the space is large enough in sectional area to give the effect of a large flue having comparatively little heating surface.

To the rear and below the fire tube drums, transversely of the boiler shell, there is provided a water drum 26 connected by means on nipples 27 to each of the fire tube drums, which, as may be seen from Figure 1, are placed in offset relation to accommodate the insertion of the nipples in the cylindrical shell portions thereof. A similar transverse steam and water drum 28 is mounted outside the main boiler shell at the forward end of the fire tube drums, each of which is in turn connected to the drum 28 by means of a second set of nipples 29, the forward ends of the drums being offset in the same manner as the rear ends for the accommodation of the nipples. Above the rear end of the fire tube drums and outside the main boiler shell there is mounted a second transverse steam and water drum 30. The two drums 28 and 30 are connected by a series of water circulators 31, and steam circulators 32. Downcomers 33 connect each end of the water space of the drum 30 with the water drum 26.

It will thus be seen that in the fire tube generating unit a continuous circulation has been provided for. The nipples 29 carry the steam and water discharge from the generating drum to the transverse steam and water drum 28, which provides the necessary liberating surface, the steam separated in drum 28 being carried over to the steam space of drum 30 through the circulators 32, where further separation may take place, and from there being discharged to the superheater. A return water circulation is provided from drum 28 through the circulators 31 to the water space of the drum 30 and thence through the downcomers 33 to the lower water drum 26, which serves to supply the evaporating drums through the nipples 27.

The fire tube evaporating unit is connected to the fire box unit by means of a series of vertical tubes 34 connecting the lower transverse water drum 26 with the water space of the transverse drum 18. These tubes serve as equalizers between the two units and also form the means for supplying feed water to the fire box unit. In addition, as will be seen from Figures 1 and 6, these tubes form a water screen across the combustion gas outlet 15 of the fire box unit. These tubes will generate steam in considerable quantity, as they are subjected not only to the radiant heat from the firebox, but also to the full volume of the combustion gasses at approximately firebox temperature, and their discharge into the drum 18 will be very violent. In order therefore to provide a steady flow of water to the nipples 19, a

5 curved baffle 35 is provided in drum 18 over said nipples, the baffle, however, not extending to the ends of the drum. Water flowing to the nipples 19 passes under this baffle from the comparatively quiet ends of the drum and a steady supply of water to the nipples and downflow headers is thus assured.

10 In order that dry steam may be taken off from the drum 18, a second baffle 36 is placed across the top of the drum above the circulators 20 and below the steam offtake 37, this second baffle also terminating at the drum heads short of the ends of the drum so that 15 the discharge from the circulators and the tubes is prevented from reaching the steam offtake 37 directly, the steam flowing to the offtake by way of the spaces at the ends of the drum.

20 As indicated in Figure 1 a considerable space is provided between the vertical tubes 34 and the rear ends of the firetube evaporating drums 23 and 24, this space being enclosed by the main boiler shell 22 and forming a location for the superheater unit. The 25 steam offtake 37 from the firebox unit and the offtake 38 from the firetube unit are connected by means of flexible expansion joints 39, in which may be incorporated steam separators, to a common superheater inlet member 40 having two branch arms which 30 connect respectively to the superheater inlet headers 41 and 42. Headers 41 and 42 are respectively connected by tubular super- 35 heater elements 43 and 44 to a common outlet header 45, from which the steam is delivered to the usual throttle indicated at 46.

40 The main boiler shell 22 is carried forward from the fire-tube evaporating unit to form a smoke-box section in which there is mounted transversely thereof an economizer, indicated generally at 47, which delivers the boiler feed water through the conduit 48 to the water space of the drum 28. The main 45 boiler shell is recessed at either side of the economizer and in the recesses so provided there are disposed a series of vertical settling tanks 49 and 50 at either side of the boiler. An exhaust steam feed water heater 51 is provided which delivers pre-heated 50 feed water through the left hand series of settling tanks 49 to the economizer. From the economizer the feed water, which has been raised to approximately boiler temperature, is delivered through the right hand series of settling tanks 50 and conduit 48 to the boiler drum 28. The economizer shown here, together with the settling tanks and arrangement thereof, is illustrated in 55 detail in my copending application Serial #3,538, filed January 19, 1925, to which reference may be had for a more detailed description.

60 Referring now to Figure 4, I have shown 65 a modified form of boiler which in the main

is similar in construction and arrangement to the form shown in Figure 1 but which is adapted to accommodate a different form of economizer. In this form the firebox and superheater units are identical with those already described and therefore need not be described in detail. The fire tube unit is also similar in general arrangement to the form shown in Figure 1 but is composed entirely of drums 23' which are somewhat longer than the corresponding drums shown in Figure 1 and which occupy the major portion of the smoke-box section. In this form, where the smaller drums are omitted, comparatively large spaces are left between the drums, which are utilized for the accommodation of a tubular economizer. In this form of construction, pre-heated feed water is delivered from the feed water heater 51' through the conduit 52 to an economizer header 53 which is suitably partitioned to cause a series flow of feed water through the tubular economizer units 54 arranged in the inter-drum spaces formed by the lower rows of drums. After traversing the first series of elements 54, the feed water passes through the nipple 55 to a second header 53', similar to header 53, and which directs the feed water serially through a second series of elements 54' arranged in the inter-drum space between the upper rows of drums. Nipple 56 connects the outlet of header 53' with a third header 56 which directs the feed water through a third series of economizer elements 54'' located between the uppermost drums and the main boiler shell. The feed water is discharged from header 56 through the conduit 57 to the water space of the forward boiler drum 28'.

65 From the foregoing description it may readily be seen that I have provided a locomotive boiler which is materially different from the usual form, over which it possesses substantial advantages which may be briefly summarized as follows:

70 The water tube construction of the firebox unit together with the novel construction and arrangement of the fire tube evaporating portion of the boiler results in the elimination of all stayed surfaces and large 75 diameter drums, and as a consequence the advantages of high pressure operation may be obtained. It is to be noted in this connection that I have provided a boiler, capable of withstanding high operating pressures, which is composed entirely of elements which may be easily and cheaply constructed in accordance with well known principles of boiler construction and with 80 existing shop facilities.

75 I am enabled, because of the water tube construction of the firebox unit employed, to provide a firebox and combustion space of greater volume than is usually the case. This results in improved combustion condi- 85

tions, a better heat transfer rate due to the large area of heating surface exposed to direct radiation from the fire, and a desirable lowering of the temperature of the combustion gases before their exit from the combustion chamber. Furthermore, because of the large grate area which it is possible to employ, a greater combustion rate may be maintained without the introduction of excessive draft and cinder losses. I obtain the regular and rapid water circulation of the most approved type of water tube boilers, with the consequent increase in the rate of evaporation and furthermore because of the form of my firebox unit I have available steam generating means which is peculiarly adapted to meet the extreme fluctuating loads encountered in locomotive practice.

By the construction and arrangement of the fire tube evaporating unit I take advantage of the full sectional area available for a locomotive, which is considerably greater than can be utilized with the ordinary cylindrical form of boiler shell. This presents a free gas area greatly in excess of that usually available, resulting in a greater possible boiler capacity. By using this section of the boiler for a fire tube evaporating unit only, I am able to provide in this space fire tube evaporating drums in which are used a large number of closely spaced, small diameter fire tubes, giving a large area of heating surface per unit of boiler length and thereby obtaining the required amount of heating surface with a unit of comparatively short length. I obtain an improved evaporating rate in the fire tube unit by the arrangement of the several elements in such manner that a definite and regular water circulation therethrough is obtained, analogous to that of a water tube boiler. The fire tube unit furthermore provides a large storage capacity and forms a reservoir of water heated to the evaporating temperature available as feed to the firebox unit, which is called upon to add only the heat of vaporization thereto in order to produce the steam necessary to meet increases in load.

By placing the superheater unit between the firebox unit and the fire tube unit, and the economizer forward of the latter unit, I obtain a water and steam flow through the boiler counter to that of the gases, and thereby obtain the most efficient rate of heat transfer. The superheater unit is placed in a high temperature gas zone where the required degree of superheat may be obtained with a minimum amount of superheating surface. This results not only in a reduction in the pressure drop through the superheater, due to the short elements employed, but also in a reduction in the obstruction to the free gas flow through the boiler because of the space occupied by the superheater elements. I further obtain the ad-

vantages of a mixed radiant and convection type superheater, as with the superheater arrangement I employ the elements thereof are exposed not only to the gases in contact therewith but also to direct radiant heat from the firebox unit. Furthermore, the amount of radiant heat reaching the superheater elements may be readily controlled by the arrangement and spacing of the water tube screen interposed between the fire box and superheater units.

Because of the short length of fire tube unit possible with my construction, I am able within a permissible overall boiler length to obtain a long and unobstructed smoke-box section, suitable for the accommodation of an economizer of sufficient area to materially increase the overall boiler efficiency by reducing the temperature of the combustion gases to a point near boiler temperature before they reach the stack.

The provision of the two series of settling tanks assures the elimination of substantially all feed water impurities before the feed water enters the boiler and because of the re-circulation of the boiler water in the fire tube evaporating section any impurities which may pass through the settling chambers will be deposited in the fire tube section before reaching the fire box unit, to which a substantially pure feed water is always supplied. This latter feature is important, as the rate of evaporation in the fire box unit is very rapid and this, together with the extreme gas temperature obtaining in this unit, makes it desirable that the evaporating surfaces thereof be kept as free from scale as possible.

What I claim is:

1. A locomotive boiler comprising a plurality of communicating evaporating units serially arranged with respect to the gas flow through the boiler, one of which forms the firebox and combustion chamber of the boiler, each of said units including a plurality of steam generating elements delivering to an element forming a steam liberating chamber and each of said units being constructed and arranged to form a definite and complete water circulating system delivering a steam and water mixture from the generating elements and returning water thereto.

2. A locomotive boiler comprising a primary water tube evaporating unit having a complete water circulation within itself, a secondary fire tube evaporating unit, said secondary unit having a complete water circulation independent of that of said primary unit, and a connection between said units whereby said secondary unit furnishes the feed water supplied to said primary unit.

3. A locomotive boiler comprising a primary water tube evaporating unit having a

complete water circulation within itself, a secondary fire tube evaporating unit, said secondary unit having a complete water circulation independent of that of said primary unit, a connection between said units whereby said secondary unit furnishes the feed water supplied to said primary unit, and a common steam offtake from said units.

5 4. A locomotive boiler comprising a primary water tube evaporating unit having a complete water circulation within itself, a secondary fire tube evaporating unit, said secondary unit having a complete water circulation independent of that of said primary unit, and a feed water connection from said secondary to said primary unit, a common steam offtake from said units, and a superheater located between said units and connected to said steam offtake.

10 5. A locomotive boiler comprising a primary water tube evaporating unit having a complete water circulation within itself, a secondary fire tube evaporating unit, said secondary unit having a complete water circulation independent of that of said primary unit, a common steam offtake from said units, and a superheater located between said units and connected to said offtake.

15 6. In a locomotive boiler, the combination with a primary water tube evaporating unit the tubes of which form the walls of a furnace and combustion space and having a definite and complete water circulation within itself, of a secondary firetube evaporating unit, having a complete water circulation independent of said primary unit and through which the combustion gases discharged from said primary unit pass, and means for abstracting additional heat from the combustion gases after the major portion of their heat has been given up to the evaporating units.

20 7. In a locomotive boiler, the combination with a primary water tube evaporating unit the tubes of which form the walls of a furnace and combustion space, and having a definite and complete water circulation within itself; of a secondary firetube evaporating unit having a complete water circulation independent of said primary unit and through which the combustion gases discharged from said primary unit pass, and a super-heater located between said units.

25 8. In a locomotive boiler, the combination of a primary water tube evaporating unit the tubes of which form the walls of a furnace and combustion space and having a definite and complete water circulation within itself, a secondary firetube evaporating unit, having a complete water circulation independent of said primary unit and through which the combustion gases discharged from said primary unit pass, a superheater located between said units, and means for ab-

stracting additional heat from the combustion gases after the major portion of their heat has been given up to the evaporating units.

30 9. A locomotive boiler comprising, in combination, a water tube primary evaporating unit having a small water volume and a definite and complete water circulation within itself, the tubes of said unit forming the walls of a furnace and combustion chamber, a secondary firetube evaporating unit having a large water volume and a definite and complete water circulation independent of said primary unit, and a water feeding connection from said secondary to said primary unit, whereby said secondary unit provides for both units a large reserve of water at evaporating temperature to meet fluctuating steam demands.

35 10. A locomotive boiler comprising, in combination, a primary water tube evaporating unit having a small water volume and a definite and complete water circulation within itself, the tubes of said unit forming the walls of a furnace and combustion chamber, a secondary firetube evaporating unit having a large water volume and a definite and complete water circulation independent of said primary unit, a water connection between said units, and an economizer delivering water at substantially evaporating temperature to said secondary evaporating unit.

40 11. A locomotive boiler comprising, in combination, a primary water tube evaporating unit having a small water volume and a definite and complete water circulation within itself, the tubes of said unit forming the walls of a furnace and combustion chamber, a secondary firetube evaporating unit having a large volume and a definite and complete water circulation independent of said primary unit, a common steam outlet connecting said units, and a superheater located between said units and connected to said outlet.

45 12. A locomotive boiler comprising, in combination, a primary water tube evaporating unit having a small water volume and a definite and complete water circulation within itself, the tubes of said unit forming the walls of a furnace and combustion chamber, a secondary firetube evaporating unit having a large water volume and a definite and complete water circulation independent of said primary unit, a water connection between said units, a common steam outlet connecting said units, a superheater located between said units and connected to said outlet, and an economizer delivering water at substantially evaporating temperature to said secondary evaporating unit.

50 13. In a water tube locomotive firebox unit, in combination, upflow and downflow headers, a steam and water drum above said downflow headers, circulators connecting

5 said drum with said downflow headers, circulators connecting said drum with said upflow headers, and a plurality of horizontally inclined tubes connecting said downflow to said upflow headers and forming the side walls of said fire-box, said tubes being exposed for the major portion of their length to radiant heat generated in the fire-box.

10 14. In a water tube locomotive firebox unit, in combination, upflow and downflow headers, a steam and water drum above said downflow headers, circulators connecting said drum with said downflow headers, circulators connecting said drum with said upflow headers, a plurality of horizontally inclined tubes connecting said downflow to said upflow headers and forming the side walls of said firebox and supplemental side wall tubes above said first named tubes, said 15 supplemental tubes connecting said downflow headers with said last named circulators.

14 15. In a water tube locomotive firebox unit, the combination with upflow and downflow headers, horizontally inclined side-wall tubes connecting said headers, a steam and water drum, and circulators connecting said drum with said downflow headers, of circulators connecting said upflow headers with said drum, said circulators carrying headers intermediate their ends, and supplemental side wall tubes connecting said last named headers with said downflow headers.

35 16. In a water tube locomotive firebox unit, a side-wall construction comprising, in combination, a vertical upflow header and a vertical downflow header, a steam and water drum above said downflow header, a circulator connecting said drum to said downflow header, a plurality of horizontally inclined sidewall tubes connecting said headers, a substantially horizontal circulator connecting said upflow header with said drum, and means providing additional water cooled side wall surface between said side wall tubes and said last named circulator.

40 45 17. In a locomotive boiler, a water tube fire-box unit comprising horizontally inclined side wall tubes, outer front and rear headers connected by said side wall tubes, intermediate front and rear headers connected to said outer headers and forming front and rear water walls, and roof tubes connected to said intermediate headers, some of said intermediate front headers being spaced apart and providing a combustion gas outlet there-between.

50 60 65 18. In a locomotive boiler, a water tube fire-box unit comprising horizontally inclined side wall tubes, outer front and rear headers connected by said side wall tubes, intermediate front and rear headers connected to said outer headers and forming front and rear water walls, some of said

intermediate front headers being spaced apart and providing a combustion gas outlet there-between, roof tubes connecting said intermediate front and rear headers above said outlet, and spaced arch tubes connecting said intermediate front and rear headers below said outlet.

5 19. In a locomotive boiler, a water tube fire-box unit comprising horizontally inclined side wall tubes, outer front and rear headers connected by said side wall tubes, intermediate front and rear headers connected to said outer headers and forming the front and rear water walls, some of said intermediate front headers being spaced apart and providing a combustion gas outlet there-between, roof tubes connecting said intermediate front and rear headers above said outlet, and a refractory roof baffle supported on said roof tubes and directing the combustion gases toward said outlet.

10 20. In a locomotive boiler, a water tube fire-box unit comprising horizontally inclined side wall tubes, outer front and rear headers connected by said side wall tubes, intermediate front and rear headers connected to said outer headers and forming front and rear water walls, some of said intermediate front headers being spaced apart and providing a combustion gas outlet there-between, roof tubes connecting said intermediate front and rear headers above said outlet, a steam and water drum mounted above said front headers, and circulators connecting said drum with said front and rear headers.

15 21. In a locomotive boiler, in combination, a primary evaporating unit having a combustion gas outlet therefrom, a secondary evaporating unit through which the combustion gases from said primary unit pass, a superheater located between said units and extending across said outlet, and a connection between the water spaces of said units, said connection passing between said combustion gas outlet and said superheater and forming a thermal screen for the latter.

10 22. In a locomotive boiler, in combination, a primary evaporating unit having a combustion gas outlet therefrom and a steam and water drum located above said outlet, a secondary evaporating unit through which the combustion gases from said primary unit pass and having a water drum located below said outlet, a superheater located between said units, and a plurality of tubes connecting said water drum with said steam and water drum, said tubes passing between said outlet and said superheater.

15 23. In a locomotive boiler, the combination of a primary evaporating unit having a complete water circulation within itself, a secondary evaporating unit comprising a plurality of fire tube drums, serially con-

nected elements connecting the end portions of said drums to form a closed water circulating path within said secondary unit in which the flow is longitudinal of said drums, 5 some of said elements providing the steam liberating surface and steam outlet for said secondary unit, and a connection between one of said elements and said primary unit whereby water is supplied to said primary unit from said secondary unit.

10 24. In a locomotive boiler, an evaporating unit comprising a plurality of fire tube drums, serially connected elements connecting the end portions of said drums to form 15 a closed water circulating path within the unit in which the flow is longitudinal of said drums, said elements forming the sole means of communication between said drums and providing the steam liberating 20 surface and steam outlet for the unit.

25 25. In a locomotive boiler, an evaporating unit comprising a plurality of parallel fire tube evaporating drums, a water drum connected to one end of each of said evaporating drums, a steam and water drum connected to the opposite end of each of said evaporating drums, whereby a direct longitudinal flow through said drums is imposed, and means of returning water from said steam 30 and water drum to said water drum.

35 26. In a locomotive boiler, an evaporating unit comprising a plurality of parallel fire tube evaporating drums, a water drum connected to one end of each of said evaporating drums and supplying water thereto, a steam and water drum, connections delivering the discharge from each of said evaporating drums to said steam and water drum, a feed water inlet in said steam and water drum, and means for conveying the feed water and the water discharged from said evaporating drums to said water drum.

40 27. In a locomotive boiler, an evaporating unit comprising a plurality of parallel fire tube evaporating drums, a water drum connected to one end of each of said evaporating drums, a steam and water drum connected to the other end of each of said evaporating drums, a second steam and water drum, steam and water circulators connecting said steam and water drums, downcomers connecting said second steam and water drum to said water drum, and a steam outlet in said second steam and water drum.

45 28. In a locomotive boiler, the combination, with a main shell through which the combustion gases make a single longitudinal pass; of a plurality of small diameter fire tube evaporating drums located longitudinally of said shell and occupying substantially the full sectional outline of said shell, and additional heat absorbing means located between said drums, and substantially filling the spaces therebetween.

50 29. In a locomotive boiler, the combina-

tion with a main shell through which the combustion gases make a single longitudinal pass; of a plurality of fire tube evaporating drums located longitudinally of said shell and occupying substantially the full cross sectional outline thereof, and additional heat absorbing means located in the spaces between said drums, said means comprising a second series of fire tube evaporating drums substantially smaller in diameter than 70 said first named drums.

75 30. In a locomotive boiler, the combination, with a main shell through which the combustion gases make a single longitudinal pass; of an evaporating unit comprising a plurality of small diameter fire tube drums located longitudinally of said shell and occupying substantially the full cross sectional area thereof, all of said drums lying wholly below the water lever in said boiler.

80 31. In a locomotive boiler, the combination, with a main boiler shell through which the combustion gases make a single longitudinal pass; of a plurality of small diameter fire tube drums located longitudinally of said shell and occupying substantially the full cross sectional area thereof, serially connected elements forming with said drums a closed water circulating path in which the flow is longitudinal of said drums, said elements including nipples connected to said drums, and said drums being offset longitudinally of each other to permit said nipples to be connected to the sides of said drums.

85 32. A locomotive boiler comprising a primary water tube evaporating unit having a complete water circulation within itself, a secondary fire-tube evaporating unit, said secondary unit having a complete water circulation independent of that of said primary unit, and means connecting said units below the normal water levels thereof to maintain a substantially common water level in the two units.

90 33. A locomotive boiler comprising a primary water tube evaporating unit having a complete water circulation within itself, a secondary fire tube evaporating unit, said secondary unit having a complete water circulation independent of that of said primary unit, and a connection between said units below the normal water levels therein, said connection serving to supply feed water from the secondary to the primary unit by gravity, and to maintain a substantially common water level in the two units.

95 34. In a locomotive boiler, the combination of a primary evaporating unit having a complete water circulation within itself and a steam outlet, a secondary evaporating unit comprising a plurality of fire-tube drums, serially connected elements connecting the end portions of said drums to form 100 a closed water circulating path within said

secondary unit in which the flow is longitudinal of said drums, some of said elements providing the steam liberating surface and steam outlet for said secondary unit, a superheater located between said units and connected to said outlet, and a connection between one of said elements and said primary unit whereby water is supplied to said primary unit from said secondary unit.

35. In a locomotive boiler, an evaporating unit comprising a plurality of fire-tube drums, arranged in parallel with respect to the gas flow through the boiler, serially connected elements connecting the end portions of said drums to form a closed water circulating path within the unit in which the flow is longitudinal of said drums, said elements providing the steam liberating surface, and steam outlet for the unit.

30 36. In a locomotive boiler, an evaporating unit comprising a plurality of fire-tube drums, arranged in parallel with respect to the gas flow through the boiler, serially connected elements connecting the end portions of said drums to form a closed water circulating path within the unit in which the flow is longitudinal of said drums, one of said elements providing a steam liberating surface, and others of said elements connecting each of said drums directly to said one element.
